LITTER BOX FOR DOMESTIC CATS

Olga C. Moberger, 133 Irving St.,
Everett, Mass. 02149

Filed Sept. 12, 1966, Ser. No. 3,815

Term of patent 14 years

Int. Cl. D30—99

U.S. Cl. D30—41

FIG. 1

FIG. 2

← 4

FIG. 3

FIG. 4

4—4 in FIGURE 2.

I claim:

The ornamental design for a litter box for domestic cats, substantially as shown.
